UNITED STATES PATENT OFFICE.

ARTHUR P. PAYNE, OF NEW HAVEN, CONNECTICUT, ASSIGNOR TO WINCHESTER REPEATING ARMS COMPANY, OF NEW HAVEN, CONNECTICUT.

HANDLAMP.

Original application filed June 9, 1920, Serial No. 387,657. Divided and this application filed June 21, 1920. Serial No. 390,538.

To all whom it may concern:

Be it known that I, ARTHUR P. PAYNE, a citizen of the United States, residing in the city of New Haven, county of New Haven, 5 and State of Connecticut, have invented certain new and useful Improvements in Hand-lamps, of which the following is a full, clear, and exact description.

This invention relates to hand lamps and 10 it pertains more especially to those of the type set forth in my application Serial No. 387,657, of which the present application is a division.

The invention has more particular reference to hand lamps of the type in which a 15 three-position switch is employed, having a movable element which assumes one position for flashing, another position for permanent lighting, and a third position, termed 20 the "safety" position, in which the switch is locked in an inoperative condition. In certain phases of the invention, however, it is unnecessary that the switch have three 25 distinct positions, as some features of my improvements may be employed to advantage in a two-position or other switch.

One of the primary objects is the provision 30 of improved means for closing and opening the circuit of a hand lamp of the insulating casing type.

By my invention, also, I provide effective means for preventing the accidental lighting 35 of the lamp when the movable switch element is in the safety position.

Other objects are to improve and simplify 40 the construction and to make the switch device compact, efficient and durable.

To these and other ends the invention 45 consists in the novel features and combinations of parts to be hereinafter described and claimed.

In the accompanying drawings:

Fig. 1 is an elevation of a tubular hand lamp embodying my improvements;

Fig. 2 is a fragmentary central longitudinal section on a larger scale, showing the switch parts in position for flashing;

Fig. 3 is a fragmentary interior view of the casing on a still larger scale;

Fig. 4 is a section on line 4-4 of Fig. 2;

Fig. 5 is a section on line 5-5 of Fig. 2;

Fig. 6 is an enlarged longitudinal section

of the main parts of the switch showing the flash position;

Fig. 7 is a similar view showing the permanent light position; 55

Fig. 8 is a similar view showing the safety position;

Figs. 9 and 10 are sections on lines 9-9 and 10-10, respectively, of Fig. 6; and 60

Fig. 11 is a detail perspective view of the member with which the push button is adapted to make contact.

I have shown my improvements applied to a tubular hand lamp of the miner's type, 65 having a casing 20 of fibre or like insulating material, containing the usual dry cells 21. At the rear end of the casing the same is provided with the customary threaded ferrule 22, onto which screws the ordinary end 70 cap 23, carrying a spring 24 that presses against the bottom of the rear cell. The cells, of which there are two in the embodiment illustrated, are encased in the customary paper insulating wrapper. At the front 75 end the casing is furnished with a metal ferrule 25 held in place by a plurality of rivets 25^a passing through the fibrous casing; and on the ferrule 25 is screwed a lens shell 26, onto which, in turn, the lens holder 27 is screwed. The lens holder supports the lens 28 and between the lens and the front end of the casing is a reflector 29 having a metal socket 30 at its inner part for the reception of the lamp bulb 31. At its periphery the reflector 29 is suitably insulated 80 from the lens shell and lens holder. The bulb 31 is located in the socket 30 in the usual manner and makes contact in the ordinary way with the central electrode of the 85 front battery cell.

Located on the exterior of the fibre casing about midway of the length thereof is a metal switch structure 33, by which the circuit containing the lamp and dry cells is 90 adapted to be closed. This switch structure includes a sheet metal base plate or member 34, which serves as a guide for a combined slide and push button structure, as herein- 95 after described. The base plate is electrically connected in a suitable manner, as by means of a brass conductor strip 35, with the uncovered bottom portion of the rear cell. Preferably the connection is from the 100

cell to the spring 24 and thence to the end cap 23 and ferrule 22, to which the conductor 35 may be riveted, as shown in Fig. 3, the rivet connection being adjacent the rear 5 end of the conductor strip, as shown at 36, and the conductor strip having at its opposite end a similar rivet connection 37 with the base plate 34. From the central electrode of the front cell the circuit passes through the 10 bulb 31 to the socket 30, through a portion of the reflector 29, thence through a conductor strip 38 to the movable part of the switch structure 33, as hereinafter described.

The conductor strip 38 is arranged within 15 and along the side wall of the fibre casing and is mounted to slide lengthwise thereof. Near its outer end portion it may be guided by one of the rivets 25^a, previously mentioned, which projects through a slot 38^a, as 20 shown in Figs. 2 and 3. At its outer end the strip 38 is curved, as shown at 39, so that the tip or extremity thereof is adapted to contact flatwise with the outer surface of the reflector at say a point about midway between the periphery of the reflector and its 25 central axis. When the contact strip is in the position shown in Fig. 2 the same will make effective contact with the reflector when the latter is placed in position in the lamp. In doing this the reflector is placed within the lens shell 26, the lens being then applied by means of its holder 27, and the reflector is thereby pressed against the curved end portion of the strip 38 so as to 30 make effective contact therewith.

At its inner portion the strip 38 is guided in a guide member 40 (Fig. 11), located adjacent a slot 41 in the fibre casing beneath the base plate 34. The guide member 40 40 may be conveniently stamped up from sheet metal and the same has a rim portion 42 extending around the slot 41 at the outside of the casing. The sheet metal blank from which the member 40 is constructed is 45 punched downwardly to provide transverse keeper members 43, 44, at the inner part thereof and a transverse contact member 45 at the outer part thereof. The parts 43, 44 and 45 are in the nature of bridges which 50 extend across from the rim portion at one side of the slot in the casing to the rim portion at the other side of the slot, the bridge 45 being intermediate the bridges 43, 44. When the member 40 has been positioned in the slot 41, the bridge member 45 is substantially in the plane of the slot, but the members 43, 44 project inwardly somewhat with reference to the casing so as to 55 form keepers for the end portion of the movable conductor strip 38. These keepers abut the conductor strip at its inner face, as shown in Fig. 6, and the strip is abutted at its outer face by the inner surface of the casing. In this manner the strip is supported and guided effectively for move-

ment lengthwise of the casing. The strip is of such length that its inner end passes inwardly beyond the slot 41 in all positions of the strip, the inner extremity bearing against the inner surface of the casing.

The switch base plate 34 is shaped to conform to the casing and it may be advantageously stamped out from sheet metal. It has a raised longitudinal rib 46, which serves as a guide for a slide piece 47 carrying a central push button 48. The guide rib 46 has a flat outer face, provided with suitable slots for positioning and guiding the slide 47. This slide 47 is of elongated shape and is adapted to slide 60 forwardly and rearwardly on the rib 46 to a limited extent. It is preferably constructed of sheet metal with a channeled cross section, having integral top and side walls, as described in my application Serial No. 387,657, filed June 9, 1920. The side walls of the slide near the corners of the latter are continued downwardly to form securing and guiding lugs or projections 49, which pass through longitudinal slots 50 in the base 65 plate and are bent laterally beneath the base plate so as to hold the slide in place. A rectangular member 51 is positioned at the under surface of the guide projection 44, and the lugs 49 pass through a central rectangular opening 52 therein at the corners of such opening, and are bent outwardly over the face of said rectangular member. In this manner the member 51 is made a part of the sliding structure whereby a substantial bearing of the slide on the base plate is afforded. At its forward portion the member 51 is bent downwardly, as shown at 53, and the downwardly bent portion is secured in a suitable manner to the movable contact strip 70 38. In the particular form shown, the portion 53 is secured to the strip 38 by means of an insulating fastener 54. The connection between the slide and the contact strip is preferably somewhat in front of the keeper 75 member 44.

At the central part of the base plate 34 beneath the slide 47, said plate is provided with a slot 55 directed lengthwise of the guide rib 46. The slot 55 is adapted to co-operate with the inner end portion of the push button 48 carried by the slide 47. The push button is located within a cylindrical socket 56 in the slide 47 at the central part thereof, said socket being formed by punching in the outer wall of the slide. The socket has a bottom wall 57 with a perforation therein in which the shank 58 of button 48 is guided for movement in an inward and outward direction. Between the bottom 80 57 of the push button socket and the head of the push button is a spring 59, which normally holds the button in the position shown in Fig. 6, that is with its inner end substantially in the plane of the guide rib 85 120 125 130

46. The inner end 58 of the button carries an enlarged portion or flange 60 that limits the outer movement of the button by making contact with the under surface of the socket bottom. The flange or collar 60 may be fitted over the inner extremity of the button shank and riveted to the same.

The shank of the push button is adapted to co-operate with the fixed contact member 10 constituted by the transverse bridge piece 45 of guide member 40. When the parts are in the flash position shown in Fig. 6, the collar 60 is located within the central portion 61 of the slot 55, which central portion 61 is rounded out and of such size as to permit the button shank to be moved freely in an inward and outward direction relatively to the fixed contact member 45. When the button is pushed inward, the inner end thereof makes contact with member 45, which is in electrical connection with the conductor strip 38 by virtue of the sliding fit of the conductor strip in member 40, and thus the circuit is closed. When the push button is released, the spring carries it back to the initial position and thus breaks the circuit.

Suppose, now, that it is desired to keep the lamp lighted for several minutes without using the hand for that purpose, it is merely necessary for the operator to depress the button 48 so that the projection 60 will pass inwardly beyond the plane of the slot 55 (in which the said projection normally stands), whereupon a forward pushing impulse is given to the button, and thereby to the slide, to carry the parts to the position shown in Fig. 7. In this position, the inner end of the button shank is against the contact strip 45 and is wedged in between the latter and the under surface of the base plate in the narrow front end portion of the slot 55. The contact is maintained because the enlargement 60 on the button shank is locked at the under surface of the base plate. This is the position for permanent lighting, and it will be observed that the parts cannot be shifted into this position from the flash position without a depression of the button preliminary to a forward sliding movement. As the button and slide go forward, the movable contact strip 38 goes forward also, owing to the connection between the strip and the slide member 51. The forward extremity of the conductor strip is shifted somewhat relatively to the reflector 29, but the contact of the strip with the reflector is nevertheless maintained, as indicated by the dotted lines in Fig. 2.

When it is desired to place the parts in the safety position, from the flash position shown in Fig. 6, the button is depressed and moved rearwardly of the casing. This carries the movable contact strip 38 rearwardly,

thus moving the forward end thereof out of contact with the reflector and thus breaking the circuit. Upon release of the push button after the slide 47 has been moved rearwardly as far as possible, the member 60 moves outwardly again within a rounded portion 62 at the rear end of the slot 55. This portion 62 is separated from the portion 61 by projections 63 at the sides of the slot, and it will be understood therefore that these projections prevent a forward movement of the button and slide, necessary for carrying the parts back to the flash position, without a preliminary depression of the push button for the purpose of disengaging member 60 from the projections 63. It will be observed that in the safety position shown in Fig. 8, the push button is moved rearwardly to such an extent that it cannot make contact with the fixed contact member 45, even if said button is depressed. Hence the circuit is interrupted at this point as well as in the locality of the reflector. In this manner, any possibility of lighting the lamp accidentally when the parts are in the safety position is practically overcome.

It will be understood from the foregoing description that my invention provides a simple, efficient and easily assembled device, in which the shifting of the movable switch parts from the flash position to the permanent light position or to the safety position cannot be effected without a preliminary depression of the push button, and the switch parts cannot be moved from the safety position to the flash position without a preliminary depression of the push button. The sliding movement of the push button is transferred very conveniently and directly to the movable conductor strip which, in the safety position, is out of contact with the reflector and provides means whereby in the safety position the circuit may be interrupted at more than one point for insuring against accidental lighting.

Various changes may be made in the details of the device as herein particularly described without departing from the scope of the invention as set forth in the claims.

What I claim is:

1. In a hand lamp, a casing, a battery therein, a bulb, a reflector in circuit with the bulb, a contact device on the casing permanently in electrical connection with the battery, a slide member mounted on said contact device, a depressible circuit controlling push button carried by said slide member, and a movable conductor strip having one end portion adapted to engage and disengage the reflector and permanently connected adjacent its other end with said slide member so as to be movable therewith.

2. In a hand lamp, an insulating casing, a battery therein, a bulb, and connections between the bulb and battery comprising a

housing secured to the casing, a slideable and depressible circuit controlling button mounted on the housing, and a longitudinally movable conductor strip within the casing having a permanent insulating connection with said button whereby the strip is adapted to be shifted by the button.

3. In a hand lamp, an insulating casing, a battery therein, a bulb, and connections between the bulb and battery comprising a housing secured to the casing, a combined circuit controlling push button and slide structure mounted on the housing, and a longitudinally movable conductor strip within the casing permanently connected with said combined push button and slide structure so as to be movable therewith.

4. In a hand lamp, a casing, an electric battery therein, a bulb, connections between the bulb and battery comprising a longitudinally movable conductor strip, and a combined circuit controlling push button and slide structure directly and permanently connected with said conductor strip for shifting the same.

5. In a hand lamp, a casing, an electric battery therein, a bulb, connections between the bulb and battery comprising a longitudinally movable conductor strip, and a combined circuit controlling push button and slide structure for shifting said strip having an insulated connection therewith.

6. In a hand lamp, a movable conductor strip and a combined push button and slide structure insulated from but directly connected with the conductor strip for shifting the same.

7. In a hand lamp, a battery, a bulb, and means to establish a circuit including said bulb and battery comprising a longitudinally movable conductor strip, a combined push button and slide structure, a fixed contact with which the push button co-operates, and a direct but insulated connection between the slide structure and conductor strip.

8. In a hand lamp, a casing, an electric battery therein, a bulb, connections between the bulb and battery comprising a longitudinally movable conductor strip, a combined push button and slide structure mounted on the casing, a fixed contact with which the push button part of said combined push button and slide structure co-operates, and means for connecting said strip directly with said combined push button and slide structure so that it is shiftable by the latter.

9. In a hand lamp, a casing, an electric battery therein, a bulb, connections between the bulb and battery comprising a slide structure mounted on the casing, a longitudinally movable conductor strip directly connected with the slide structure, a push button associated with the slide structure, and means for preventing movement of the slide except after an inward thrust on the push button.

10. In a hand lamp, a casing, an electric battery therein, a bulb, means for establishing an electrical connection between the bulb and battery comprising a longitudinally movable conductor strip, a slide structure mounted on the casing, a connection between the strip and slide structure whereby the former is shifted by the latter, a push button associated with the slide structure, a fixed contact member with which the push button co-operates, and means for preventing movement of the slide except after an inward thrust on the button.

11. In a hand lamp, a casing, an electric battery therein, a bulb, connections between the bulb and battery comprising a longitudinally movable conductor strip, a slide structure mounted on the casing, a connection between the strip and slide structure whereby the former is shifted by the latter, a push button associated with the slide structure, a fixed contact member with which the push button co-operates to complete the lamp circuit, and means for preventing movement of the slide except after an inward thrust on the button, said fixed contact member being in permanent electrical connection with said movable conductor strip.

12. In a hand lamp, a casing, an electric battery therein, a bulb, connections between the bulb and battery comprising a longitudinally movable conductor strip, a slide structure mounted on the casing, a connection between the strip and slide structure whereby the former is shifted by the latter, a push button associated with the slide structure, a fixed contact member with which the push button co-operates to complete the lamp circuit, and means for preventing movement of the slide except after an inward thrust on the button, said fixed contact member being in permanent electrical connection with said movable conductor strip, and said strip being insulated from said slide structure.

13. In a hand lamp, an insulating casing, a battery therein, a bulb, and means for connecting the battery and bulb, including a conductor strip within the casing, a slide structure on the exterior of the casing permanently connected with said strip, a depressible button associated with the slide structure, a fixed contact member electrically connected to the slide with which the button makes contact when depressed, and means for locking the slide structure against movement, controlled by said push button.

14. In a hand lamp, an insulating casing, an electric battery therein, a bulb, and connections between the bulb and battery, including a base plate on the casing, a slide on the base plate, a conductor strip beneath the base plate directly connected with the slide, a keeper member for guiding the con-

ductor strip, and a button associated with the slide adapted to be electrically connected to said keeper member.

15. In a hand lamp, a casing, an electric battery therein, a bulb in said casing, and connections between the bulb and battery, including a keeper member associated with the casing wall, a contact strip guided in said keeper member, a slide connected with 10 but insulated from said contact strip, and a contact device on the slide co-operating with said keeper member in closing and opening the circuit.

16. In a hand lamp, an insulating casing 15 having a slot therein, a keeper member positioned in said slot, a conductor strip guided lengthwise in the keeper member, a plate overlying the keeper member and fixed to the casing and an operating device for 20 the conductor strip mounted on said plate and having a contact device co-operating with said keeper member for making and breaking the circuit.

17. In a hand lamp, a casing, a battery 25 therein, a bulb, and means for establishing a circuit through said battery and bulb, including a movable conductor element, a switch for completing or interrupting the circuit through said element, and a slide to 30 move said element and permanently connected thereto, but insulated therefrom.

18. In a hand lamp, a casing, a battery therein, a bulb, and means for establishing a circuit through said battery and bulb, including a movable conductor element, a depressible push button to establish and interrupt a circuit through said element, and a slide having a permanent connection with 40 said element by which the latter may be moved.

19. In a hand lamp, a casing, a battery therein, a bulb, and means for establishing a circuit through the bulb and battery, including a movable conductor element within the 45 casing, a slide without the casing and permanently connected to the conductor element to move the latter, but insulated therefrom, and means for establishing and interrupting the circuit through said slide and conductor element.

20. In a hand lamp, a casing, a battery therein, a bulb, and means for establishing a circuit through the bulb and battery, including a movable conductor element within 55 the casing, a slide without the casing and permanently connected to the conductor element to move the latter, and means upon said slide for establishing and interrupting the circuit through said conductor element.

60 21. In a hand lamp, a casing, a battery therein, a bulb, and means for establishing a circuit through the bulb and battery, including a movable conductor element within the casing movable to operative and inop-

erative positions, a slide for moving said element and permanently connected thereto, and means upon the exterior of the casing for momentarily passing the current through said contact member when in its operative position.

70 22. In a hand lamp, a casing, a battery therein, a bulb, a reflector in circuit with the bulb, a contact device on the casing permanently in electrical connection with the battery, a slide member mounted on said 75 contact device, a depressible circuit controlling push button carried by said slide member, and a movable conductor strip having one end portion adapted to engage and disengage the reflector and permanently connected adjacent its other end with said slide member so as to be movable therewith, but normally insulated therefrom.

80 23. In a hand lamp, a casing, a battery therein, a bulb, means for establishing a circuit through the bulb and battery including a conductor strip movable lengthwise of the casing, a manually operable slide permanently connected to said strip and by means of which it may be shifted, and movable means 90 accessible at the outer part of the slide for controlling the sliding movement thereof.

85 24. In a hand lamp, a casing, a battery therein, a bulb, means for establishing a circuit through the bulb and battery including a conductor strip movable lengthwise of the casing, a manually operable slide permanently connected to said strip and by means of which it may be shifted, and means for locking the slide against movement including a member carried thereby and movable relatively thereto for releasing the slide.

95 25. In a hand lamp, a casing, a battery therein, a bulb, electrical connections including a movable conductor strip within the casing, a slide without the casing permanently connected to said strip to move the same, and a locking button carried by the slide and cooperating with a fixed part of the lamp structure.

100 26. In a hand lamp, a casing, a battery therein, a bulb, electrical connections including a movable conductor strip within the casing, a slide without the casing permanently connected to said strip to move the same, and a spring pressed locking member carried by the slide and cooperating with a fixed part of the lamp structure.

105 27. In a hand lamp, a casing, a battery therein, a bulb, electrical connections including a movable conductor strip within the casing, a slide without the casing permanently connected to said strip to move the same, and common means carried by said slide to close the circuit through the contact strip and to lock the slide in a predetermined position.

110 28. In a hand lamp, a casing, a battery therein, a bulb, electrical connections includ-

ing a movable conductor strip within the casing, a slide without the casing permanently connected to said strip to shift the same longitudinally of the lamp structure, and means including a depressible member on the slide for locking the latter in either of two distinct positions longitudinally of the lamp structure.

29. In a hand lamp, a casing, a battery 10 therein, a bulb, and electrical connections including a movable conductor strip within the casing, a slide without the casing to move the conductor strip and connected in fixed relation thereto, and means movably mounted 15 on the slide for locking the latter against movement.

30. In a hand lamp, a casing, a battery 20 therein, a bulb, and electrical connections including a movable circuit closing conductor strip guided on the casing, an actuator for said strip permanently connected thereto and accessible for manual operation, and

a light flashing device carried by and movable with said actuator.

31. In a hand lamp, a casing, a battery 25 therein, a bulb, and electrical connections including a movable circuit closing conductor strip guided on the interior of the casing, an actuator for said strip permanently connected thereto and accessible for manual 30 operation, and a light flashing device accessible at the exterior of the casing for manual operation.

32. In a hand lamp, a casing, a battery 35 therein, a bulb, and electrical connections including a movable circuit closing conductor strip guided on the casing, an actuator for said strip permanently connected thereto and accessible for manual operation and a combined light flashing and locking device 40 associated with said actuator.

In witness whereof, I have hereunto set my hand on the 17th day of June, 1920.

ARTHUR P. PAINÉ.
